UNITED STATES PATENT OFFICE.

CHARLES W. BOND, OF TOLEDO, OHIO.

CAR-COUPING.

SPECIFICATION forming part of Letters Patent No. 292,278, dated January 22, 1884.

Application filed September 13, 1883. (No model.)

To all whom it may concern:

Be it known that I, CHARLES W. BOND, of Toledo, in the county of Lucas and State of Ohio, have invented an Improvement in Car-Couplings, of which the following is a specification.

My invention consists of certain improvements in car-couplings, which will be fully understood from the following description and claim.

In the accompanying drawings, Figure 1 is a top view of my improved car-coupling connecting two cars. Fig. 2 is a side view of the same. Fig. 3 is a top view of the coupling not connecting the two cars.

The chief object of my invention is to provide a car-coupling which will serve to connect two cars of different heights and at the same time be simple in construction and efficient in operation.

In the accompanying drawings, A represents the car-body, and B the bumper, upon the top of which is pivoted a hook or coupling-link, C, having a coiled spring, D, at-

tached to the heel thereof, so that the coupling-link may have a horizontal swing in passing the draft-pin E on the opposite car. This draft-pin drops into a hole in the bumper-head, and is also supported by an arm, F, Fig. 2, considerable space being allowed between the bumper and the arm F, so that the hook C will not strike the bumper or the arm in coupling cars of different heights. The lever G extends horizontally to the side of the cars, and serves to lock and unlock the coupling-hook, the end of lever G being arranged to drop into the locking-bar H, which is provided with several notches, h.

Having described my invention, what I claim is—

The pivoted hook or coupling-link C, provided with the spring D, in combination with the draft-pin E upon the opposite car, substantially as and for the purposes set forth.

CHAS. W. BOND.
